VALVE GUIDE PULLER

William H. Nichols and James P. Ferguson,
South Bend, Ind.

Application March 30, 1939, Serial No. 264,890

10 Claims. (Cl. 29—88.2)

This invention relates to improvements in valve guide pullers. Automobile mechanics frequently experience considerable difficulty in removing the valves of internal combustion engines by reason of the sticking of the valve guide. Certain internal combustion engines are manufactured with the valve, valve guide, and valve spring applied thereto in preassembled unitary relation, with the valve guide removable but retained by a keeper against which the valve spring acts to hold the assembly in operative position. The engine block has a seating aperture for the valve guide which is of a size when new to initially permit ready application of the valve guide therein, but after a substantial period of engine operation during which carbon collects in the aperture around the guide it becomes very difficult to release the guide to permit the removal of the valve assembly. Furthermore, inasmuch as the keeper holds the guide against outward movement, it becomes necessary to force the guide inwardly for release of the keeper before the assembly can be pulled out. Various devices heretofore marketed to pull the guide have consequently solved only part of the problem, and the major problem of the mechanic who had the prior of tools available was to release the guide initially for the purpose of removing the keeper.

It is therefore the primary object of this invention to provide a valve guide puller by which the guide may be manipulated to release the keeper and thence to pull the guide.

A further object is to provide a device of this character by means of which a valve assembly may be applied to an engine block as well as removed therefrom.

A further object is to provide a device of this character comprising a sleeve mounting a puller element having an extension adapted to bear on said guide.

A further object is to provide a device of this character comprising a sleeve mounting a puller element having a spring pressed tiltable jaw normally maintained in operative position thereto by said sleeve.

Other objects will be apparent from the description and appended claims.

In the drawing:

Fig. 1 is a fragmentary vertical cross-sectional view of an engine block, and illustrating the first step in the use of this device.

Fig. 2 is a view similar to Fig. 1 and illustrating the second step in the use of this device.

Fig. 3 is a view similar to Fig. 1 and illustrating the final step in the use of this device.

Fig. 4 is a longitudinal sectional view of the device in inoperative position with certain parts illustrated in elevation.

Fig. 5 is a view similar to Fig. 4 illustrating the device in operative position.

Fig. 6 is an end view of the device.

Fig. 7 is an end view of the puller element per se.

Referring to the drawing, which illustrates the preferred embodiment of the invention, the numeral 10 designates an engine block from which the cylinder head has been removed. The engine block includes the usual cylinders 11, receiving pistons 12, valve seats 13, valved passages 14 and valve guide mounting 15. Valves 16 adapted to bear on valve seats 13 each include an elongated stem 17 passing through mounting 15 and slideable in a guide 18 seated in mounting 15. Guide 18 has a groove therein receiving a keeper 19 bearing against the inner end of the mounting 15. An expansible coil spring 20 encircles the inner end of valve stem 17 and bears at its opposite ends against guide 18 and a retainer 21 on the end of the valve stem. It will thus be seen that the spring tends to normally seat valve 16, and to hold the guide 18 in desired position by pressing against the same and thereby pressing keeper 19 against mounting 15.

The valve guide puller 25, best illustrated in Figs. 3 to 7, comprises an elongated metal sleeve 26 having one end face 27 thereof bearing the same angular relation to the sleeve axis that the valve stem 17 bears to the upper face of engine block 10. The wall of the sleeve is also preferably outwardly swaged at 28 adjacent face 27 for purposes to be hereinafter set forth. At the end of sleeve 26 opposite face 27, an end cap 29 is mounted on the sleeve, said cap being centrally apertured.

A puller assembly is carried by the sleeve, and includes an elongated threaded shaft 30 passing freely through the aperture in cap 29. At one end thereof the shaft 30 fixedly mounts a head 31 having a guided sliding fit in sleeve 26. A semi-cylindrical wall 32 projects outwardly from head 31 and has an angularly inwardly directed shoulder portion 33 formed integrally therewith in spaced relation to head 31. A reduced tapering end portion 34 of arcuate cross section adapted to fit closely around valve stem 17 projects from shoulder 33.

Head 31 is notched at 35 opposite wall 32, and within this notch seats jaw member 36 of arcuate cross section and wider than notch 35. Jaw member 36 is notched at 37 intermediate its ends,

with said notches 37 cooperating with notch 35 of head 31 to tiltably seat member 36 on the head. One end of jaw member 36 has an inner shoulder 38 spaced from head 31 the same distance as shoulder 33 for cooperation therewith to form a substantially continuous circular shoulder. The opposite end of jaw member 36 is connected to head 31 by a pair of coil springs 39 normally tilting said jaw member relative to the head 31.

The head 31 and jaw member 36 are mounted in sleeve 26, with jaw member 36 preferably aligned with sleeve off-set 28. A nut 40 is threaded on shaft 30 and adapted to bear on cap 29. A driving head 41 is mounted on the outer end of shaft 30. The shaft 30 is of a length sufficient to permit at least part of wall 32 and of jaw member 36 to project from the open end of sleeve 26, whereby the jaw member 36 may tilt outwardly under the action of springs 39, with the tilting action limited by swaged off-set 28 of said sleeve. When the parts are drawn fully into the sleeve, the latter serves as a retainer therefor and also as a guide for jaw member 36, holding the latter in operative coaxial relation to wall 32.

The use of the device is as follows: When the cylinder head, manifolds, etc., have been removed from the engine whose valves and guides are to be pulled, a suitable tool 42 is employed to lift the valve and valve stem against the action of spring 20 to permit the end portion 32 of the puller to be forced behind the valve head 16 until the head 16 seats on shoulder 33. The parts are arranged in position illustrated in Figs. 1 and 4 for this insertion, with jaw member 36 tilted to avoid interference thereof with the valve head. When the tool has been inserted properly around the valve and its stem, the same will assume a position with its shaft 30 in axial alignment with valve stem 17, whereupon the sleeve 26 is slid down over head 31 and jaw member 36 to cause the shoulder 38 of the latter to also seat against the valve 16. Then the tool can be rotated as necessary to present face 21 of the sleeve 26 in parallel relation to the top of the engine block while member 30 remains aligned with valve stem 17. Nut 40 is then positioned close to driving head 41 and spaced from sleeve cap 29. As soon as the shoulder 33 seats behind valve 16, the use of tool 42 can be dispensed with.

The parts now assuming the position illustrated in Fig. 2, with the end portion 34 bearing on guide 18, the shaft 18 may be struck at head 41 by hammer 43. The hammer blows are transmitted through shaft 30, head 31, and walls 32 and 34 direct to the guide, so that the latter is driven downwardly in its mounting 15 to position the guide for ready removal of its keeper 19. During this operation only a minimum amount of shock or stress is transmitted to the valve head 16 and jaw 36 by reason of the fact that the blows are directed against only the guide 18, so that only vibration or the like, rather than direct impact, is imparted to the valve, its stem, and jaw 36.

When the keeper has been released, the parts are positioned as illustrated in Fig. 3, with sleeve end 27 bearing on the engine block and nut 40 bearing on cap 29. A wrench 44 is then used to turn nut 40 for the purpose of pulling on shaft 30 and connected parts whose shoulders 33 and 38 engage behind valve 16 to pull thereon. The sleeve 26 holds the shouldered parts in operative relation to pull the valve, and the align-

ment of shaft 30 and valve stem 17 insures a straight pull on the valve which will not bend the valve or jam the parts. The force of the pull exerted by rotating the nut is fully adequate to withdraw the tightest guide.

The device may be similarly employed to reinsert the valve assembly by mounting the valve therein with its head 16 supported at shoulders 33 and 38, then applying the assembly in operative relation to the engine block 10 and guide mounting 15, and then pounding on shaft 30 as in Fig. 2 until the guide is properly positioned to receive a new keeper, after which the tool can be removed by holding the valve stem raised, sliding the sleeve 26 on the shaft 30 to permit freeing of the tilttable jaw member 36, and then manipulating the device to release the head mounted part of the device.

It will thus be seen that the device affords facilities for the performance of all operations connected with release, removal and reinsertion of a valve and guide assembly. Of these, the extension of the fixed jaw for engagement with the head to permit downward pounding of the guide, and the tilttable jaw which tilts merely upon projection from the housing or sleeve so as not to interfere with manipulation of the fixed jaw in relation to the valve during application and removal are of greatest importance in this device and mark definite advances in and improvements over the devices heretofore developed and used in the art.

We claim:

1. A valve guide puller comprising a sleeve, a rigid recessed head slidable in said sleeve and having an internal shoulder intermediate its ends, and means for pulling said head in said sleeve including a shaft fixed to said head, said recessed head being adapted to fit around the stem of a valve to bear on the valve guide while the valve head is supported on said shoulder.

2. A valve guide puller comprising a sleeve, and an elongated pulling element slidable in said sleeve, said pulling element having a recessed part adapted to engage a valve head to pull thereon, and an integral extension projecting from said part for end engagement with the valve guide.

3. A valve guide puller comprising a sleeve, and an elongated pulling member slidable in said sleeve, said member having a hollow head having an arcuate inwardly directed shoulder adapted to seat behind the head of a valve and an extension of arcuate cross section fitting around the stem of the valve and bearing on the valve guide at its end.

4. A valve guide puller comprising a housing open at one end, and having a restricted opening at its opposite end, an elongated shaft shiftable longitudinally in said opening, means for pulling said shaft longitudinally, a hollow head fixedly secured on said shaft and having an internal shoulder, and a longitudinally extending portion of arcuate cross section projecting from the shoulder and of a length at least equal to the normal spacing of said head from said guide.

5. A valve guide puller comprising a housing open at one end and having a restricted aperture at its opposite end, a shaft projecting through said aperture, a hollow head fixed on said shaft and open at one side thereof, an inwardly directed projection on the end of said head, and a member carried by said head at the open side thereof and tilttable relative thereto, said member having an inwardly directed projection at

its end, said tiltable member being normally held against tilting by said housing.

6. A valve guide puller comprising a housing open at one end and having an apertured cap at its opposite end, a shaft slidable in said aperture, a head fixed on said shaft, a fixed jaw carried by said head, and a second jaw tiltably carried by said head, said housing holding said last named jaw against tilting when disposed therein.

7. The construction defined in claim 6, wherein said head is notched and said tiltable jaw has a reduced width portion intermediate its length seated in said notch and normally confined therein by said housing.

8. The construction defined in claim 6, and spring means connecting said head and the inner end of said tiltable jaw for tilting said jaw upon partial projection from said housing.

9. The construction defined in claim 6, wherein in said housing has an outwardly flared portion at its open end, and said tiltable jaw is spring pressed for tilting said jaw when adjacent said flared portion.

10. Means for manipulating the valve and guide assembly of an internal combustion engine comprising a housing, a head slidable in said housing, a jaw fixed on said head, a jaw tiltably mounted on said head, an elongated shaft fixed to said head and projecting from said housing, and a longitudinal extension on said fixed jaw engaging said guide for dislodging said guide when said shaft is hammered, said jaws being confined by said housing to pull on said valve when said shaft is pulled.
